AMPLITUDE LIMITING SYSTEM

Frank J. Bingley, Chestnut Hill, and Robert C. Moore, Philadelphia, Pa., assignors to Philco Radio and Television Corporation, Philadelphia, Pa., a corporation of Delaware

Application January 12, 1942, Serial No. 426,524

11 Claims. (Cl. 250—20)

This invention relates to frequency modulation receivers, and more particularly to an amplitude limiting system for frequency modulation receivers.

It has been common practice to use some sort of limiting system in frequency modulation receivers and usually these limiting systems have required the amplification of the signal to a very high value, the cutting off of the undesired portion of the signal, and the amplification of the remaining portion. This system of limiting has had the disadvantage of wasting a great deal of the amplifier gain.

The purpose of limiting devices in frequency modulation receiving systems is to eliminate the effects of noise and static which appear on the received carrier mostly as amplitude modulation. This amplitude modulation carries no intelligence, and it is, therefore, advantageous to remove it in the course of amplifying the signal.

The principal object of the present invention is to provide a novel method and means for eliminating amplitude modulation from an incoming frequency-modulated carrier wave.

Another object of the invention is to provide a limiter, or amplitude-modulation remover, which does not require the wasting of a great deal of the gain of the amplifier.

A further object of the invention is to provide a limiter which does not necessitate a separate limiter tube.

Still another object of the invention is to provide a novel method and apparatus whereby amplitude modulation is eliminated from a frequency-modulated carrier wave by first modifying the wave so as to level the radio frequency signal voltage peaks on one side of the wave, whereby amplitude modulation appears only on the opposite side, and then selecting a portion of the modified wave so as to remove the amplitude modulation on said opposite side.

Other objects and features of the invention will be apparent to those skilled in the art from the following specification and the accompanying drawings, in which:

Fig. 1 is a block diagram of a frequency modulation receiver embodying the invention;

Fig. 2 is a circuit diagram of part of the second and third intermediate frequency amplifiers of the receiver shown in Fig. 1; and

Fig. 3 illustrates the signal voltage as it appears in successive parts of the receiver, the successive forms of the signal voltage being shown with respect to a time axis *t* at zero signal or ground level. Referring first to Fig. 1, there is shown a fre-

quency-modulation receiver having a suitable dipole antenna 1 connected by a transmission line 2 to a matching transformer 3, which preferably supplies the received frequency-modulated carrier signal to a radio frequency stage 4. This stage 4 may consist of one or several vacuum tube amplifiers. If desired, however, the stage 4 may be omitted entirely. The output of the radio frequency stage is coupled to the tuned converter stage 5 into which is also injected the output of the oscillator 6, which may be tuned by a section of a variable gang condenser so as to cause a desired beat or intermediate frequency in the converter, as is well known in superheterodyne receivers. In the case of frequency-modulation receivers, this intermediate frequency is often established at 4.3 mc.

The carrier wave is amplified in several stages at intermediate frequency, and in the present case there are shown three intermediate amplifier stages, the first of which, 7, is an intermediate amplifier stage of conventional design, and the second and third of which, 8 and 9, are specially designed stages embodying the present invention. The output of the third intermediate frequency stage is supplied to the second detector 10 which may be advantageously of the "balanced" type, to cause a further reduction of noise.

The detected signal is then applied to the audio frequency amplifier 11, which in turn is connected to the sound translating device 12, e. g., a loudspeaker, transcription machine, or other device.

In Fig. 2 there is shown a circuit diagram of the second and third intermediate frequency amplifiers illustrating the preferred embodiment of the invention. The first intermediate frequency amplifier 7, which produces an output voltage wave, as shown in Fig. 3 at A, may be coupled to the pentode amplifier tube 13 by means of a double-tuned transformer 14. The plate 28 of the pentode amplifier is coupled to a divided load circuit 15 and 16, the portion 15 consisting of the I. F. transformer 17 having a primary coil 18 and a secondary coil 19, the primary and secondary coils being tuned to the intermediate frequency by the condensers 20 and 21, respectively. The second portion 16 of the load circuit comprises a resistor 22 and an I. F. by-pass condenser 23. The pentode tube 13 is biased to near cut-off in any suitable manner and consequently, in addition to its operation as an amplifier, it also functions as a biased detector tube with regard to amplitude-modulation on the intermediate frequency wave. The signal voltage applied to the control grid 29 of tube 13 is shown at B in Fig.

3, while the plate current of the tube is shown at C. The displacement of the axis of signal voltage B from the axis t corresponds to the bias voltage. As a result of the plate current C, there will appear on the anode of the pentode 13 an amplified voltage, e. g., as shown in Fig. 3 at D, containing the same amplitude and frequency-modulation as is present on the voltage wave B. The displacement of signal voltage D from axis t corresponds to the D. C. voltage of the plate supply. Now since the tube 13 is acting as a biased detector, there will also appear across the resistance 22 in the load circuit a voltage which is proportional to the amplitude-modulation envelope of the signal applied to the control grid. This voltage is that shown at E in Fig. 3. Since the resistance 22 is by-passed by the condenser 23 which has low impedance at the intermediate frequency, no appreciable intermediate frequency component will appear across the resistor 22. There will also appear in the plate circuit of the tube 13 higher harmonics of the intermediate frequency, but since there is no loading impedance resonant to these harmonics, they will produce no voltage in succeeding stages.

Appearing across the secondary coil 19 of the I. F. transformer 17 will be a voltage wave having the characteristics of the voltage wave impressed on the control grid of tube 13. Appearing across the resistor 24, which is coupled to resistor 22 by means of the coupling condenser 25, will be a voltage wave having the characteristics of the amplitude-modulation of the original wave. Since coil 19 and resistor 24 are in series with respect to the input circuit of the third I. F. amplifier tube 26, there will be applied to the control grid 30 of this tube a composite signal voltage which is equal to the sum of the intermediate frequency signal voltage across the secondary winding 19 and the audio frequency signal voltage across the resistor 24. Such composite signal voltage is shown at F in Fig. 3. The effect of combining the I. F. and audio signal voltages (D and E) is to level the positive I. F. signal voltage peaks, whereby amplitude-modulation appears only on the negative side of the carrier wave. By a proper selection of the impedance characteristics of the I. F. and A. F. portions of the circuit, the relative values of these two voltages and the relative phase of the voltages may be made such that the positive peaks of the I. F. wave are brought to a common level and hence show no effects of amplitude-modulation, all of the amplitude-modulation being on the negative side of the I. F. voltage wave. The signal voltage, as applied to control grid 30 of tube 26 and with a D. C. bias component added, is shown at G in Fig. 3.

The term "peak levelling" as used in various forms in this specification, may be defined as that operation upon an amplitude-modulated wave which consists in reforming the wave about its zero axis in a manner such that all R. F. voltage peaks on one side of the wave reach a common absolute voltage level. A levelled wave is characterized in that its zero axis is effectively distorted in such a way that all of its amplitude modulation is transferred to that side of the wave whose R. F. voltage peaks are not levelled. Leveling is not to be confused with the operation known as "limiting" which is accomplished by cutting off the wave peaks.

In order to eliminate the effects of the amplitude-modulation appearing on the negative side of the voltage wave G, the tube 26 is biased below its cut-off value which is indicated by the broken

line c, so that only the positive part of the voltage wave is effective to cause output current in the plate circuit of the tube. By properly selecting the value of bias on the grid of the tube 26, the amplitude-modulation can be entirely cut off without materially affecting the amplification of the stage. The plate current of the tube 26 will be as indicated at H in Fig. 3, and the I. F. signal voltage appearing across the tube output or load impedance 27 will be without amplitude-modulation, as is shown at I in Fig. 3.

Thus, it will be seen that amplitude-modulation of a frequency-modulated carrier wave is eliminated according to the present invention by first modifying the wave so as to level the carrier signal voltage peaks on one side of the wave, thereby eliminating amplitude changes on that side, and then selecting a portion of the modified wave so as to reject the amplitude-modulation on the other side. Moreover, this is done by deriving from the wave a high frequency signal voltage and a low frequency signal voltage, the latter corresponding to the amplitude-modulation frequency, and then combining the two derived signal voltages to obtain the desired modified signal.

There is available in the output circuit of the tube 13 an amount of total power which has a definite finite maximum value, and the division of power between the I. F. and A. F. portions of the load circuit of said tube will be determined by the relative impedances of these two portions. Since it is desired to balance out the amplitude changes on one side of the carrier wave, it is necessary to carefully select these impedance values so as to obtain the balancing action. It is possible to design a radio frequency circuit to give a phase shift to correspond to any audio frequency circuit so that if the A. F. circuit is designed first, the R. F. circuit may be readily designed to correspond.

It is important in the design of this system that the phase of the amplitude-modulation wave shown at E in Fig. 3 be in phase with the amplitude-modulation envelope on the intermediate frequency wave shown at D. The more exact this phase coincidence, the more effective will be the limiter.

In Fig. 3 of the drawings it is to be understood that the relative amplitudes of the waves are not intended to be illustrated. In actual practice there would be a wide divergence of amplitudes in the various parts of the circuit, for example, the wave shown at D in Fig. 3 would be many times the amplitude of the wave shown at B in Fig. 3.

It will be found necessary to supply a certain minimum signal strength to the limiter to get effective operation, for unless the composite signal voltage is of sufficient strength to make the positive wave tops uniform and the negative wave tops always reach the cut-off point of the tube, some amplitude-modulation will come through, and the amount of amplitude-modulation which does come through will be proportional to the amount that these tops fail to reach the cut-off value.

While the limiting system of the invention has been illustrated and described as used with variable condenser tuning means, it is intended to be used with any tuning means, whether capacitive or inductive, continuously variable or otherwise. Moreover, the particular circuit illustrated and described is not to be considered as limiting of the invention, for there are numerous modifications which might be made by one skilled in the radio

art to vary the specific form of the invention without departing from its scope as defined by the appended claims.

We claim:

1. A method of reducing amplitude variations of a frequency-modulated carrier wave, which comprises deriving from said wave a signal voltage having the same frequency characteristics and including said amplitude variations, deriving from said wave a second signal voltage corresponding to the envelope of said wave, combining the derived signal voltages so as to produce a modified signal voltage in which the peaks on one side are substantially leveled, and selecting a portion of said modified signal voltage substantially free of amplitude variations.

2. In a radio receiver adapted for the reception of frequency-modulated carrier waves, apparatus for reducing amplitude variations of a received carrier wave, comprising means for deriving from said wave a signal voltage having the same frequency characteristics and including said amplitude variations, means for deriving from said wave a second signal voltage corresponding to the envelope of said wave, means for combining said derived signal voltages so as to produce a modified signal voltage in which the peaks on one side are substantially leveled, and means for selecting a portion of said modified signal voltage substantially free of amplitude variations.

3. In a radio receiver adapted for the reception of frequency-modulated carrier waves, apparatus for reducing amplitude variations of a received carrier wave, comprising means for deriving from said wave a signal voltage having the same frequency characteristics and including said amplitude variations, means for rectifying a portion of said wave to derive a second signal voltage corresponding to the envelope of said wave, means for combining said derived signal voltages so as to produce a modified signal voltage in which the peaks on one side are substantially leveled, and means for selecting a portion of said modified signal voltage substantially free of amplitude variations.

4. In a radio receiver adapted for the reception of frequency-modulated carrier waves, apparatus for reducing the effects of undesired amplitude-modulation on a received carrier wave, comprising an electron discharge tube having an output circuit and arranged to operate both as an amplifier and as a detector, a first load impedance in the output of said tube having relatively high impedance at radio frequency and relatively low impedance at lower frequencies, a second load impedance in the output of said tube for developing a voltage corresponding to the envelope of said carrier wave, whereby a resultant signal wave is produced, and means for transmitting a portion only of said resultant wave substantially free of amplitude variations.

5. In a radio receiver, a source of frequency-modulated carrier wave signal, a vacuum tube, means for supplying said signal to said vacuum tube, means for biasing said tube so that it operates both as an amplifier and as a detector, thereby to produce a variation in plate current which is proportional to the low-frequency amplitude-modulation component on the carrier wave, a resonant load circuit responsive to the carrier-frequency output of said vacuum tube, a non-resonant load circuit responsive to the low frequency variations in said plate current, a second vacuum tube amplifier having an input

circuit, means for biasing said second tube substantially to cut-off, and connections for applying the sum of the signal voltages across said load circuits to the input circuit of said second vacuum tube.

6. A system for limiting a radio frequency wave to substantially remove amplitude-modulation therefrom, comprising means for amplifying the wave, means for rectifying a portion of the wave, means for superimposing the rectified component on said amplified radio frequency wave, the phase and amplitude of said rectified component being such as to level the positive peaks of the radio frequency wave, means for removing the negative portion of said wave, and means for further amplifying the positive portion of said wave.

7. In an amplitude-limiting circuit, a source of high frequency alternating current signal voltage, means for establishing a low frequency signal voltage whose wave form corresponds substantially to the envelope of said high frequency signal voltage, means for combining said signal voltages in such relative proportions that the positive signal voltage peaks of the high frequency signal voltage all reach substantially the same absolute voltage, and means responsive to said positive peaks for establishing a new high frequency alternating current signal voltage of substantially constant amplitude.

8. The method of deriving a frequency-modulated high frequency signal wave substantially free of amplitude modulation from an incoming signal wave which is both frequency-modulated and amplitude-modulated, which method consists, first, in detecting said incoming signal wave to derive therefrom a low frequency wave corresponding to the amplitude modulation of said incoming wave; secondly, combining the signal wave and the derived low frequency wave with the latter substantially in phase with the envelope of the negative side of said signal wave, and; thirdly, limiting the amplitude of the resultant signal wave to such extent as substantially to cut off amplitude modulation on the negative side only of said resultant signal wave.

9. The method of deriving a frequency-modulated high frequency signal wave substantially free of amplitude modulation from an incoming signal wave which is both frequency-modulated and amplitude-modulated, which method consists, first, in detecting said incoming signal wave to derive therefrom a low frequency wave corresponding to the amplitude modulation of said incoming wave; secondly, impressing the signal wave and the derived low frequency wave, concurrently, upon the control electrode of a vacuum tube amplifier, with said low frequency wave substantially in phase with the envelope of the negative side of said signal wave, and; thirdly, limiting the amplitude of the resultant signal wave in the plate circuit of said amplifier to such extent as substantially to cut off amplitude modulation on the negative side only of said resultant signal wave.

10. In a signal receiving system, a source of high frequency incoming waves having both frequency modulation and amplitude modulation, a detector coupled to said source and operative to derive therefrom a low frequency wave corresponding to said amplitude modulation, a vacuum tube amplifier having a control electrode coupled to said detector to receive therefrom a low frequency voltage corresponding to said derived low frequency wave, a plate circuit for said

amplifier, said control electrode being coupled to said source to receive, concurrently with said low frequency voltage, a high frequency voltage corresponding to said incoming wave, the two voltages thus impressed upon said control electrode being so co-related that the low frequency voltage is in phase with the negative side of the envelope of the high frequency voltage and substantially equal in amplitude to the co-incident amplitude variation of said negative side, and means negatively biasing said control electrode to such extent that the negative side of the resultant high frequency wave in the plate circuit of said amplifier is limited in amplitude sufficiently to exclude at least the greater part of the amplitude modulation therefrom.

11. In a signal receiving system, a first vacuum tube amplifier biased to function as a detector and amplifier, a source of incoming signal waves having both frequency modulation and amplitude modulation, the input side of said first amplifier being coupled to said source, a

second vacuum tube amplifier having a control electrode and a plate circuit, coupling means between the output side of said first amplifier and the control electrode of said second amplifier for transmitting to said control electrode an amplified voltage corresponding to said signal wave, together with a low frequency voltage wave derived from said signal wave and corresponding to the amplitude modulation thereof, said coupling means being operative to maintain the low frequency voltage wave which is impressed upon said control electrode in phase with the envelope of the negative side of the signal wave voltage impressed upon said control electrode, and means negatively biasing said control electrode sufficiently to cut off amplitude modulation from the negative side of the signal wave appearing in the plate circuit of said second amplifier.
